UNITED STATES PATENT OFFICE.

SIDNEY T. SJOBERG, OF MINNEAPOLIS, MINNESOTA

FUSE-PLUG.

1,233,720.

Specification of Letters Patent. Patented July 17, 1917.

Application filed February 21, 1916. Serial No. 79,482.

To all whom it may concern:

Be it known that I, SIDNEY T. SJOBERG, citizen of the United States, resident of Minneapolis, county of Hennepin, State of Minnesota, have invented certain new and useful Improvements in Fuse-Plugs, of which the following is a specification.

My invention relates to multiple fuse plugs or to that type in which a plurality 10 of fuse wires are employed to avoid the necessity of removing the plug and inserting a new one every time a fuse wire is burned out.

The object of my invention is to provide 15 a multiple fuse plug of extremely simple construction and one which can be manufactured and sold at a comparatively low price.

Other objects of the invention will appear from the following detailed description.

20 The invention consists generally in various constructions and combinations, all as hereinafter described and particularly pointed out in the claims.

In the accompanying drawings forming 25 part of this specification,

Figure 1 is an outside view of a fuse plug embodying my invention,

Fig. 2 is a longitudinal sectional view,

Fig. 3 is a transverse sectional view taken 30 on line $x-x$ of Fig. 2,

Fig. 4 is a sectional view taken on line $y-y$ of Fig. 2.

In the drawing, 2 represents one member 35 of the plug, composed of insulating material, preferably porcelain, and 3 the other member, also preferably of porcelain. These members have a central orifice 4 there-

through to receive a contact pin 5, the members revolving on the pin to shift the circuit 40 from one fuse wire to another. This pin has a head 6 at the inner end forming a contact surface and an insulating washer 7 is provided between said head and the metal sleeve 8 to prevent any possibility of arcing

45 at this point. This sleeve is exteriorly threaded for engaging the threads of the socket, as usual in fuse plugs of this type.

A tongue 9 of suitable material, preferably brass and forming a spring contact, 50 is mounted at one end on the sleeve 8 and projects up through a hole 10 in the flanged upper end of the member 2 and into a recess 11 that is formed in the lower end of the plug member 3, the walls of said recess depending and encircling the upper end 55 of the tongue or spring contact. The mem-

ber 3 is provided with a plurality of holes or sockets 12 therein extending through the same from end to end and there may be any desired number of these holes, according to 60 the number of fuse wires to be used.

13 represents the fuse wires, each having a concave cap 14 attached to one end thereof and fitted into the inner end of a socket 12 adjacent to the recess 11, the fuse wires extending centrally through the sockets and having their opposite ends soldered at 15 to a head 16 formed on the opposite end of the pin 5 from the head 6. This head has projections 17 thereon, arranged to extend between the ribs 18 formed on the end of the porcelain member 3 and operating as stops to prevent the head and pin from turning in the block and breaking the connection with the fuse wires. The fuse wires are centered 70 in the sockets 12 by suitable insulation 19 which is fitted into the ends of the sockets, as shown in Fig. 2. An insulated cap 20, preferably of metal, is fitted over the plug member 3 and a portion of its walls is 80 threaded to engage the threads on the end of the insulating member. The plug member 3 has numerals thereon opposite the fuse wires to enable the user of the plug to readily determine when all of the wires have 85 been burned out.

The contact spring 9 has an end surface 21 that is formed to fit the concave surface of the caps 14 and make a rubbing contact therewith as one member of the plug is 90 revolved upon the other, thereby readily shifting the circuit from one fuse wire to the other.

The device is of very inexpensive construction, is composed of but few parts, and the 95 shifting from one fuse wire to another can be easily and quickly performed.

I claim as my invention:

1. A multiple fuse plug comprising a contact pin having heads on the ends thereof, 100 insulating members mounted on said pin for relative rotation, a shell contact carried by one of said members, a contact spring connected with said shell contact, the other member having a plurality of longitudinal 105 sockets extending therethrough and encircling said pin, insulating caps mounted in one end of said sockets, conducting caps mounted in the opposite ends of said sockets, fuse wires connected with said conducting 110 caps and extending through said sockets and through said insulating caps and con-

nected to one end of said pin, and said contact spring being positioned to successively engage said conducting caps when one member is revolved with respect to the other.

5. 2. A multiple fuse plug comprising a contact pin having heads on the ends thereof, insulating members mounted on said pin for relative rotation, one of said members having a recess in the end thereof opposing the 10 other member and provided with a plurality of holes encircling said pin and communicating with said recess, a shell contact carried by said other member and a contact spring mounted on said shell contact and projecting 15 into said recess to a point adjacent the lower ends of said holes, a series of contact caps mounted in the lower ends of said holes in position to engage said contact spring upon relative rotation of said members, fuse 20 wires connected with one end of said pin and also connected respectively with said caps through said holes, the rotation of one member with respect to the other causing said contact spring to successively engage 25 said caps:

3. A multiple fuse plug comprising a contact pin, insulating members mounted on said pin for relative rotation, one of said members having a recess in the end thereof opposing the other member and provided 30 with a series of holes leading from one end into said recess, a shell contact carried by said other member and having a slotted

opening therein and a contact spring mounted on said shell contact and projecting 35 through said opening into said recess and extending to a point adjacent said holes, a series of contact caps mounted in the lower ends of said holes and positioned to engage the said contact spring when one of said 40 members is revolved with respect to the other member, fuse wires arranged in said holes and connected at one end with said pin and at their other ends with said caps, and said caps and spring having concave and convex 45 engaging surfaces.

4. A multiple fuse plug comprising an insulating member, a contact pin whereon said member is centrally mounted, said pin having a head at its end that is seated against said member, said member having ribs formed thereon with recesses between them and said head having lugs projecting into said recess and held by said ribs against revolution with respect to said member, and said member having a series of fuse wires mounted therein and attached to said lugs, contact caps connected with said fuse wires, a second insulating member, a shell contact carried thereby and having a conductor for 60 engaging with said contact caps when one insulating member is revolved with respect to the other member.

In witness whereof, I have hereunto set my hand this 15th day of February 1916.

SIDNEY T. SJOBERG.
